UNITED STATES PATENT OFFICE.

OSWIG SCHLENSTEDT, OF DUISBURG, GERMANY.

PRESS FOR MAKING TUBES.

1,150,394.

Specification of Letters Patent. Patented Aug. 17, 1915.

Application filed November 13, 1913. Serial No. 800,823.

To all whom it may concern:

Be it known that I, OSWIG SCHLENSTEDT, engineer, a subject of the Emperor of Germany, residing at Duisburg, Rhine, Germany, have invented certain new and useful Improvements in Presses for Making Tubes, of which the following is a specification.

The present invention relates to an improvement in tube presses of the kind in which for perforating the block of metal and for forming the tube a mandrel is employed which is held stationary after the block of metal has been perforated, as soon as its front end has entered so far into the die, that the forming of the tube is possible. In the hitherto known presses of the aforementioned kind a separate cylinder arranged within the press plunger or behind the press cylinder is provided for operating the mandrel. In the former instance this cylinder travels together with the press plunger until the perforation has been completed and the perforating mandrel has been rendered stationary, whereupon the cylinder within the press plunger advances over the perforating plunger in connection with the mandrel. In the other instance the perforating mandrel is advanced independently of the press plunger and, as soon as it has been rendered stationary, the press plunger is advanced independently. These presses necessitate a very complicated gearing, so that their economy is, in many instances, rendered doubtful.

According to the present improvement the mandrel is likewise provided with one or several cylinders, but these cylinders at the same time serve as idlers or cylinders for the inoperative stroke of the press ram, and as soon as the perforating ram has been rendered stationary, the press ram can pass over it, without any reversal of the operating gear for the supply or discharge pipes of the perforating mandrel being necessary.

In the accompanying drawing an embodiment of this improvement is exemplified in Figures 1 to 3 in diagram and in three different operative positions.

In these drawings *a* is the press cylinder, to which also the cylinders *b* of the plungers *h* for the perforating punch *f* may be connected.

c is the press plunger, *d* the cross head of the latter and *e* the press ram connected to *d*.

f is the combined perforating punch and mandrel; the crosshead *g* of which is con-

nected to the plungers *h* working in the cylinders *b*.

i is the withdrawing cylinder, the piston *k* of which is coupled by the rods *m* with the crosshead *d* of the press ram.

n is the container, *r* is the block of metal; *s* is the matrix and *x*, *x* are stops for the crosshead of the mandrel *f*. These stops may be adjustable.

The operation of the arrangement is as follows: When the metal block *r* is being introduced into the container *n*, the press cylinder *a* must be connected with the supply pipe, while the withdrawing cylinder *i* connects with the discharge pipe or with an accumulator. The perforating cylinders *b* are put under pressure, so that the perforating punch *f* advances; the crosshead *d* with the press plunger *c*, the press ram *e*, the rod gear *m* and the withdrawing piston *k* participating in such advance. After the block has been introduced into the container and has been perforated, the perforating punch or mandrel *f* has the position shown in Fig. 2, its crosshead *g* abutting against the stops *x*. Now the press cylinder *a* is put under pressure so that the crosshead *d* with the press ram *e* and the withdrawing piston *k* alone advances until the whole block has been pressed out in form of a tube *y*. Thereupon the cylinders *a* and *b* are brought into connection with the discharge pipe and the withdrawing cylinder *i* is put under pressure or the withdrawing piston *k* is released to the action of the pressure prevailing in *i*. Then the crosshead *d* with the parts connected thereto will first return until it abuts against the crosshead *g*. Thereupon also the pistons *h* and the perforating punch or mandrel *f* are returned into their initial position, as shown in Fig. 1.

I claim:

1. A two-stage tube press having a ram, a combined punch and mandrel and a die therefor; means for advancing said punch during the first stage of operation, other means for advancing the ram during the second stage of operation, means for arresting said punch during said second stage, and means for retracting said ram; said punch engaging with said ram during said first stage to drive the ram forward and said ram engaging with said punch to retract the punch.

2. In a tube press having a main ram, a punch and a corresponding die, said punch

also serving as mandrel, means for advancing the ram and the punch together while the hole is being punched in the blank and other means for subsequently advancing 5 said ram alone, means for subsequently retaining the punch in fixed position while the ram continues to advance to finish the tube and other means for retracting said ram, said punch engaging with said ram during 10 the punching movement and said ram engaging with said punch during its retracting movement, thereby retracting the punch.

3. In a tube press having a main ram, a punch and a corresponding die, said punch 15 also serving as mandrel; a housing having separate working cylinders with pistons for the ram and the punch, said punching cylinder and piston causing simultaneous advancement of the punch and the ram during 20 the first part of the forward stroke while the cylinder and piston for said ram remain idle; abutment members for the punch holding said punch stationary while said ram-cylinder and piston are active during the 25 latter part of the forward stroke of the ram.

4. In a tube press having a main ram, a punch and a corresponding die, said punch also serving as mandrel; a stationary housing having separate working cylinders with 30 pistons for the ram and the punch, said punch-piston and cylinder working alone during the first part and said ram-piston and cylinder working alone during the second part of the pressing stroke; a cross head

each for said ram and said punch rigidly 35 connecting them with their respective pistons, and a retracting cylinder connected with said ram cross head, said cross heads inter-engaging during the first part of the pressing stroke and the last part of the re- 40 tracting stroke.

5. In a tube press having a main ram, a punch and a corresponding die, said punch also serving as mandrel; separate working cylinders in a common stationary housing 45 with pistons for the ram and the punch; a cross head each for said ram and said punch rigidly connecting them with their respective pistons and inter-engaging during the first part of the forward stroke but disengaging during the last part of said stroke, and a retracting cylinder connected with said ram cross head; abutment members engaging with said punch cross head after completion of its forward stroke and retaining 50 the punch cross head in fixed position during the completion of the forward stroke of said ram, said cross heads inter-engaging during the first part of the pressing stroke and the last part of the retracting stroke. 55

The foregoing specification signed at Barmen, Germany this 31st day of October, 1913.

OSWIG SCHLENSTEDT. [L. s.]
